UNITED STATES PATENT OFFICE

HARVEY D. GEYER, OF DAYTON, OHIO, ASSIGNOR TO THE INLAND MANUFACTURING COMPANY, OF DAYTON, OHIO, A CORPORATION OF DELAWARE

LOCKING HANDWHEELS

Application filed December 11, 1924. Serial No. 755,185.

This invention relates to locking handwheels and is especially adapted for steering wheels for motor vehicles to prevent unauthorized use thereof.

5 This invention embodies a number of improvements over the locking wheel disclosed in application, Serial No. 755,182, by Harvey D. Geyer and Alva W. Scott, filed December 11, 1924.

10 An object of this invention is to provide a positive safety means for preventing the accidental displacement of the locking bolt from its driving position in the event of breakage of the spring which ordinarily holds 15 the bolt in driving position, or from other possible causes.

A more specific object is to provide such a safety means on the lock itself by only a slight change in the structure thereof, where- 20 by additional mechanism and consequent complication is avoided and a very effective safety means is provided.

Further objects and advantages of the present invention will be apparent from the following description, reference being had to the accompanying drawings, wherein a preferred form of embodiment of the present invention is clearly shown.

In the drawings:

25 Fig. 1 is a vertical section on line 1—1 of Fig. 2 showing the invention embodied in a loose locking steering wheel for automobiles.

Fig. 2 is a section on line 2—2 of Fig. 1.

30 Fig. 3 is a vertical section on line 3—3 of Figs. 1 and 2, but shows the lock barrel and bolt shaft in elevation.

35 Figs. 4 and 5 are detail views of the lock showing the barrel in its non-rotary or "safety" position that occurs when the bolt is in driving position as shown in Fig. 2.

40 Figs. 6 and 7 are similar to Figs. 4 and 5 but show the barrel in the position where it can be rotated by means of the lock key.

45 Fig. 8 is an end view looking in the direction of arrow 8 of Fig. 6.

Fig. 9 is a detail of the fixed plate which cooperates with the rotary barrel to form a stop means therefor.

50 In the drawings similar reference charac-

ters refer to similar parts throughout the several views.

The invention has been illustrated as embodied in a loose locking steering wheel for automotive vehicles. The central portion of 55 the metal spider of the handwheel is shown at 11 and the automobile steering shaft with which it is associated at 12. The steering shaft 12 has an upper tapered end 13 and a threaded portion 14 at its topmost end. A 60 socketed journal head 15 fits snugly down over the tapered end 13 and is suitably keyed thereto by the key 16. A round nut 20 is screwed down upon the threaded end 14 which thus firmly anchors the head 15 against axial 65 removal from shaft 12.

A hardened steel shell member 25 is journaled upon the head 15 and nut 20 by means of the upper ball bearing 21 and the lower ball bearing 22, as clearly illustrated in Fig. 70 1. This shell member 25 is provided with a bottom cover plate 26 which has threaded engagement therewith as shown at 27, which threaded engagement permits the proper adjustment of the ball bearings 21 and 22 at 75 any time, as will be readily understood from the drawings.

The head 15 is provided with one or more lateral recesses 28 (three being shown in Fig. 2) to receive a locking bolt 30 for locking the shell 25 fixed to said head 15 or to permit relative rotation therebetween. The bolt 30 (preferably made of three layers of stamped sheet steel as shown in Fig. 2) is rigidly fixed upon the bolt pin 31, the ends 80 of which pin 31 serve as journals for mounting the bolt in the protective shell 25 so that it may be swung to various positions in the bolt chamber 32 as will presently be described (see Fig. 1).

85 A key controlled barrel lock 35 is mounted at one end of pin 31 and the rotatable barrel 36 of said lock is held in driving engagement with pin 31 by the flat lug 37, extending within the flat groove or slot 38 in pin 31. 90 In machining the bolt chamber 32 the metal of shell 25 is cut away at the right side as viewed in Fig. 3, which thus facilitates the proper machining of chamber 32 as well as the other recesses in shell 25 clearly shown 95 100

in Fig. 3. This cut away metal is replaced by a hardened steel bushing 40 which is pressed into place and held retained in its proper position by the driven pin 42 whose outer end lies flush with the bottom of shell 25 and hence cannot be removed by a thief after once being driven in place. The stationary bushing of lock 35 is permanently held in place in the steel bushing 40 by a small driven pin 43 as clearly shown in Fig. 2. It will be clear from Figs. 1 and 2 that the bushing 40 must have an arcuate portion 44 cut out of one side thereof in order to clear the head 15, and a second and deeper arcuate portion 45 cut out in order to clear the bottom cover plate 26 and so permit its assembly upon the shell 25.

A coil spring 46 surrounds pin 31 and has one end secured to said pin while the opposite end is held stationary by means of the fixed pin 48. This coil spring 46 urges bolt 30 to rotate in a clockwise direction (as viewed in Fig. 1) into recess 28 and thus fix the steering wheel in driving position upon shaft 12 as shown in full lines in Figs. 1 and 2.

The barrel lock will now be described.

The rotatable barrel 36 of the lock is held against rotation by the ordinary lock tumblers 100 when key 49 is withdrawn. When the key 49 is inserted therein (as shown in Figs. 6 and 7) the barrel 36 may be rotated by means of the key, all as is well known in the art. This invention however provides for a sliding movement of the barrel 36 whereby a positive stop is provided at a predetermined position of said barrel even though the key remains inserted. For this purpose a flat plate 101 having a straight edge 102 is fixed to the stationary bushing 35 of the lock as clearly shown in Fig. 8. The projecting driving head 103 of the rotary barrel 36 is provided with a flange 104 which overlies the straight edge 102 of plate 101 and thus prevents the outward sliding movement of barrel 36 except in one position of said barrel 36. When in this certain position a small flat 105 on flange 104 registers with the straight edge 102 as clearly shown in Figs. 7 and 8, and it is obvious from the drawings that the barrel 36 may now slide outward a short distance until the lug 106 engages the top of plate 101 as clearly shown in Fig. 5. When the barrel 36 is in its "out" position, as shown in Figs. 4 and 5, the cooperating flats 102 and 105 will positively prevent any rotation of said barrel. In order that the barrel 36 may be turned by the key 49 it is necessary that the barrel 36 be pressed by the key 49 to its "in" position, as shown in Figs. 6 and 7, whereupon the barrel 36 may be rotated in either direction by the key 49 since the flange 104 will then lie above the plate 101 and the flats 102 and 105 consequently do not engage. In the application of this improved form of barrel

lock with the mechanism which is to be operated thereby a yieldable means is arranged to urge the barrel 36 to its "out" or "safety" position. With such an arrangement it is obvious that as soon as the flats 102 and 105 register when the key 49 is turned the barrel 36 will automatically snap into its "out" or safety position.

In the embodiment illustrated in the drawings, the barrel 36 is continuously urged to its "out" position by the small coil spring 107 contained in the central recess in the bolt shaft 31 (see Fig. 2). Preferably a small plunger 108 having a shank extending within the coil spring 107 is provided to give a good bearing contact between the spring 107 and the end of the flat driving lug 37. In Figs. 1, 2, and 3 the lock bolt 30 is shown in driving position, that is, the steering wheel is fixed upon the shaft 12. When bolt 30 is in this position the flats 105 and 102 are in register and hence the barrel 36 is urged by the small coil spring 107 to its "out" position as clearly shown. The flats 105 and 102 will now positively prevent the bolt 30 from being jarred out of engagement with the recess 28 in the event of the breakage of the main coil spring 46 and thus the bolt 30 is positively held in "safe" driving position, the key 49 remaining in the lock.

In order to render the wheel loose or inoperative the operator first presses the key inwardly until the barrel 36 slides to the position shown in Figs. 6 and 7 against the urge of the small spring 107 and then swings the bolt 30 about 180 degrees to the position 30', (shown in dotted lines in Fig. 1) by means of key 49 and then withdraws the key from the lock. The lock tumblers 100 will then engage with the barrel 36 in the ordinary manner and hold the bolt 30 in its inoperative position and thus prevent any unauthorized use of the machine. In order to again render the wheel operative the key 49 is inserted in the lock to release the tumblers 100 whereupon main spring 46 will swing bolt 30 against the head 15. The wheel is then rotated until one of the recesses 28 registers with the bolt 30 whereupon bolt 30 will snap into the recess 28, after which the lock barrel 36 is automatically pressed out to safety position by the small spring 107.

The method of assembling the parts of the wheel lock mechanism together and attaching it to the steering shaft will now be described. The protective shell 25 is inverted and the ball bearing 21 and nut 20 inserted therein, the bolt 30 being in the position 30'. The socketed head 15 is next dropped in against the nut 20 and the bolt 30 swung into one of the recesses 28. The bottom cover plate 26 and the ball bearing 22 are then inserted and the cover plate 26 is screwed into the shell 25 until the proper adjustment of both ball bearings 21 and 22 is obtained. A

small set screw 53 accessible from the outside may be provided for holding the exact adjustment of cover plate 26. Now when the bolt 30 is again swung to its inoperative position 30' it will be impossible to unscrew the cover plate 26 more than half a revolution at most, since one or more lugs 50 (two being shown in Fig. 1) are provided upon the inner surface of cover plate 26, which lugs will 5 strike the heel of bolt 30 as clearly shown by the dotted lines 30' in Fig. 1. It is thus obvious that a thief cannot remove cover plate 26 and disassemble the wheel when bolt 30 is in inoperative position.

15 The steering wheel spider 11 is preferably attached to the protective shell 25 after the above described assembly has been made. The metal spider 11 is rigidly secured to the shell 25 by the two screw bolts 54 and thus 20 the spider 11 and shell 25 become in effect a single structure.

The assembled wheel is attached to the steering shaft 12 as follows. The assembled wheel is placed over the tapered end of shaft 25 12 with a key 16 in its proper position the top thread of the threaded portion 14 abutting the bottom thread of nut 20. This round nut 20 has its lower outer edge cut away in order to clear the path of bolt 30 as clearly shown 30 in Fig. 1. A short lug 60 rigid with nut 20 projects into this cut-away annular groove 61 lying between nut 20 and head 15. When bolt 30 is rotated counterclockwise 90 degrees from the full line position of Fig. 1 to 35 the position 30'', the toe 62 of bolt 30 will lie in the annular groove 61 and therefore will engage the lug 60 if the wheel is revolved relative to the nut 20. The wheel may now be turned loosely about head 15 since the bolt 30 40 is entirely out of engagement with head 15 and thus the bolt 30 will act as a wrench to screw nut 20 down upon the threaded portion 14 of shaft 12 until head 15 is pressed home upon the tapered portion 13. This intermediate position 30'' of bolt 30 may be 45 termed the assembly position of the bolt since it is used only in assembling or disassembling the wheel and shaft. Obviously the wheel may be removed from the shaft only by one 50 in possession of the key since otherwise the bolt cannot be turned to its assembly position 30''.

The horn button 85 and horn switch mechanism 74 shown in the drawings form no 55 part of the invention claimed in this application and hence are not described in detail herein. It is obvious however that the presence or absence of this horn switch mechanism does not affect the method of operation or of assembly of the lock mechanism as described hereinabove.

While the form of embodiment of the present invention as herein disclosed, constitutes a preferred form, it is to be understood that 60 other forms might be adopted, all coming

within the scope of the claims which follow. What is claimed is as follows:

1. In combination, a locking bolt, a lock for actuating said bolt, said lock comprising a fixed bushing and a rotary barrel therein, operable by a key, said barrel being reciprocatable within said bushing to a non-rotatable or safety position when the bolt is in a predetermined position, and means for automatically moving said barrel to said safety position, whereby a positive stop is provided for preventing the accidental displacement of said bolt from said predetermined position. 70

2. In combination, a locking bolt, a lock having a rotary barrel and a fixed bushing, a driving connection between said barrel and bolt whereby said bolt is actuated, said barrel being reciprocatable within said bushing to a non-rotary position when at a predetermined rotary setting whereby said bolt is held against actuation when in said predetermined setting. 80

3. In combination, a locking bolt, a lock having a rotary barrel and a fixed bushing, a driving connection between said barrel and bolt whereby said bolt is actuated, said barrel being reciprocatable within said bushing to a non-rotary position whereby said bolt is held against actuation when in a predetermined position, and means for automatically reciprocating said barrel to its non-rotary position when said bolt is moved to said predetermined position. 90

4. A tumbler lock having a rotary barrel and a fixed bushing therefor, said barrel having a driving head projecting from the inner end of said bushing, means associated with said driving head for permitting a slight longitudinal movement of said barrel when at a predetermined rotary setting and for preventing rotary movement of said barrel after the longitudinal movement thereof has taken place. 100

5. In combination, a tumbler lock having a rotary barrel and a fixed bushing therefor, a member having driving connection with said barrel whereby said member is rotated to a plurality of positions, said barrel being reciprocatable within said bushing to a non-rotary position when said member is in a predetermined position, whereby said member is positively held against accidental movement when in said predetermined position. 110

6. A tumbler lock having a rotary barrel and a fixed bushing therefor, said barrel being capable of an axial extension from its normal position within said bushing at a predetermined rotary setting thereof, and safety means for positively preventing rotary movement of said barrel when in said axially extended position. 120

7. A tumbler lock having a rotary barrel and a relatively fixed bushing therefor, a plurality of divided tumblers arranged in normally opposed recesses in said barrel and 130

bushing respectively for normally holding said barrel locked to said bushing, said barrel being also capable of an axial movement from its normal position within said bushing when 5 said tumbler divisions are in alignment by a suitable key, and spring means for urging said barrel into an axially moved position whereat said normally opposed tumbler recesses are not opposed.

10 In testimony whereof I hereto affix my signature.

HARVEY D. GEYER.
